CLAIM

The ornamental design for a fruit/vegetable netting display hammock, as shown and described.

DESCRIPTION

FIG. 1 is a perspective view of the fruit/vegetable netting display hammock showing my new design taken from the front and to one side;

FIG. 2 is a side elevational view thereof;

FIG. 3 is a top plan view thereof;

FIG. 4 is a bottom view thereof;

FIG. 5 is an end view thereof; and,

FIG. 6 is a perspective view of a second embodiment taken from the top and to one side.

The broken line showing of fruit and vegetables in FIGS. 1 and 6 is for illustrative purposes only and forms no part of the claimed design;

FIG. 1

FIG. 2

FIG. 3

FIG. 4

FIG. 5

FIG. 6
